A. G. F. KUROWSKI

TYPEWRITING MACHINE

Filed Aug. 12, 1919

Inventor:
Alfred G F Kurowski
by D B Stickney
Attorney

UNITED STATES PATENT OFFICE.

ALFRED G. F. KUROWSKI, OF BROOKLYN, NEW YORK, ASSIGNOR TO UNDERWOOD
TYPEWRITER COMPANY, OF NEW YORK, N. Y., A CORPORATION OF DELAWARE.

TYPEWRITING MACHINE.

Application filed August 12, 1919. Serial No. 317,042.

To all whom it may concern:

Be it known that I, ALFRED G. F. KUROWSKI, a citizen of the United States, formerly a citizen of Germany, residing in Brooklyn 5 Borough, in the county of Kings, city and State of New York, have invented certain new and useful Improvements in Typewriting Machines, of which the following is a specification.

10 This invention relates to key-tops for typewriter key-levers, and an object is to provide a readily detachable key-top, and one which can be removed and replaced without the use of tools.

15 A feature of the invention relates to the provision of a cup, mounted on the key-stem, and a ring which engages the cup, and is detachably connected to the stem. Preferably, the cup is freely mounted on the key-20 stem, so that the ring serves to hold the cup in place.

Other features and advantages will hereinafter appear.

In the accompanying drawings,

25 Figure 1 is a perspective view of a key-stem, showing my improved top applied thereto.

Figure 2 is a side elevation of the key-stem.

30 Figure 3 is a front view.

Figure 4 is a side elevation of the key-stem alone, showing the slots with which the spring detents of the key-ring engage.

Figure 5 is a sectional view.

35 Figure 6 is a composite view, in perspective, of the key-cup, key-paper and glass.

Figure 7 is a bottom view of the key-ring.

The key-lever 1 is provided with a key-stem 2, and engaging the top of the key-stem 40 is a key-cup 3, which may be of the usual form. Said cup, however, does not fit tightly onto the key-stem, but freely engages the same. The cup has the usual flange 4. In order to hold the key-cup in position on the key-stem, a key-ring 5 is provided, said ring having an overturned flange 6, which engages the top of the usual glass 7, under which, and fitting within the flange of the cup, is a key-paper 8, bearing the character 45 or characters corresponding to the type carried by the key-lever. The key-ring is so bent as to engage the under side of the cup, and is provided with a pair of detent springs 9, having angular portions 10 which en-

50 gage respectively in recesses shown as a pair 55

of detent-receiving slots 11 in the key-stem. The spring detents 9 are yieldable to permit the angular projections 10 to escape from the slots 11, or to release the detent-engaging means formed by these slots, thereby to enable the key-top as a whole to be detached from the stem 2. It is desirable to provide two slots in the key-stem, because, if the key-stem is quite thin, and only one slot were provided the angles of the spring detents 60 would clash and prevent them from properly holding the key-top in position on the key-stem.

When it is desired to change the key-top, all that is necessary is to apply slight force 70 to the key-top, in order to unseat the detents from the slots, when the whole key-top may be removed and another substituted.

Variations may be resorted to within the scope of the invention, and portions of the 75 improvements may be used without others.

Having thus described my invention, I claim:

1. In a typewriter key, the combination with a key-stem, of a key-cup freely fitting 80 said stem, and a key-ring engaging said cup and detachably secured to said stem.

2. In a typewriter key, the combination with a key-stem, of a key-cup mounted on said stem, a key-ring, and means for detachably securing said key-cup to the stem 85 through the medium of said ring.

3. In a typewriter-key, the combination with a key-stem having a detent-receiving recess therein, of a detachable key-top comprising a key-cup and a key-ring, and a spring detent carried by said ring for engagement in said recess in the stem and yieldable out of said recess to enable the detachment of the key-top from the stem. 95

4. In a typewriter key, the combination with a key-stem, of a key-top comprising a key-cup and a key-ring, and spring detents carried by said ring for engagement with said stem. 100

5. In a typewriter-key, the combination with a key-stem provided with detent-engaging means, of a detachable key-top comprising a key-cup and a key-ring, and a spring detent carried by said ring for automatic engagement with said means and automatically yieldable to release said means to enable the detachment of the key-top from the stem. 105

6. In a typewriter key, the combination 110

with a key-stem, of a key-cup having a stem-receiving socket mounted on said key-stem, a key-paper and glass in said cup, and a flanged ring engaging said cup and clamping said key-paper and glass, said ring being provided with spring means engaging said stem and movable to release said ring.

7. In a typewriter key, the combination with a key-stem having a slot, of a key-cup having a stem-receiving socket mounted on said key-stem, and a flanged ring engaging said cup and having spring means engaging said slot and movable to release said ring.

8. In a typewriter-key, the combination with a key-stem having therein a pair of detent-receiving slots, of a detachable key-top comprising a key-cup and a key-ring, and a pair of spring detents carried by said ring and engageable respectively in said slots and yieldable therefrom to enable the detachment of said key-top from said stem. 15 20

ALFRED G. F. KUROWSKI.
